UNITED STATES PATENT OFFICE.

JOHN ALBERT MARKLEY, OF CLIFTON FORGE, VIRGINIA, ASSIGNOR OF ELEVEN-TWENTIETHS TO JAMES BAILY AND JOSEPH B. WORTH, OF WILMINGTON, DELAWARE.

COMPENSATOR FOR RAILWAY-SIGNALS.

SPECIFICATION forming part of Letters Patent No. 589,606, dated September 7, 1897.

Application filed July 1, 1896. Serial No. 597,682. (No model.)

To all whom it may concern.

Be it known that I, JOHN ALBERT MARKLEY, a citizen of the United States, residing at Clifton Forge, in the county of Alleghany and State of Virginia, have invented certain new and useful Improvements in Compensators for Railway-Signals; and I do hereby declare the following to be a full, clear, and exact description of the invention, such as will enable others skilled in the art to which it appertains to make and use the same.

This invention relates to compensators, but more particularly to those employed for keeping a proper tension upon the wires or connections which extend from the signal-station to operate a signal or other movable body located at a distance therefrom.

The primary object of my invention is to provide a simple and inexpensive compensator for creating a proper tension upon the wires extending from the signal-station to the signal, so as to adjust said wires and to keep the signal and the operating-lever located in the signal-station or other convenient position in their proper relative positions with respect to each other, so that no matter how much the wires may expand or contract by the heat or cold or otherwise there will be little, if any, danger of operating the main lever without placing the signal in its proper position.

Other objects are to provide means whereby the force necessary to operate the signal-wires is reduced to a minimum, and to provide compensating devices which may be readily applied to the operating-levers of signal-stations without reconstructing or materially altering either the station itself or the arrangement of the levers therein.

Further objects are to provide means located convenient to the operator by which he may readily ascertain or be notified that the signal has not responded to the movement of the main lever either on account of the chains or connections slipping or by becoming detached from said lever, and to provide means to engage a portion of the compensating devices in order to secure a substantially rigid connection between said compensating devices and the main lever when the latter is operated.

Heretofore where separate wires were used

for operating a signal, such as an ordinary semaphore blade or arm, to a "safety" or "danger" position it has been proposed to connect the ends of the wires at the signal-station by an endless chain passing over pulleys carried by the operating-levers and provided with a weight suspended from said endless chain in order to take up the slack and keep a tension upon the wires. It has also been proposed to provide a lever with blocks provided with cam-surfaces or a sliding or other portion connected with the wires and provided with a single weight to compensate for expansion or contraction in said wires. In such constructions the action of the weight upon the chain or connection makes it difficult to operate the main lever or separate clutch or ratchet-and-pawl mechanism has to be provided, in which case the parts are more or less complicated or the liability of operating the lever without moving the signal is materially increased, owing to the tendency of the clutch or gripping mechanism to slip upon the chain.

To overcome the above-mentioned and other objectionable features in such devices, I provide a compensator which consists in the construction and combination of the several parts, substantially as hereinafter described, and then more particularly defined in the claims at the end of the description.

Referring to the accompanying drawings, forming a part of this specification, Figure 1 is an elevation, partly diagrammatic, of my invention, illustrating the manner of connecting the same with an ordinary semaphore or signal. Fig. 2 is an end view of one of the weighted pulleys and the manner of arranging the chains thereon, and Figs. 3 and 4 are modified forms of weighted pulleys.

In the drawings, A may designate a suitable standard provided with a rack b at or near its upper end adapted to be engaged by a spring-pressed pawl b', arranged upon a lever B and operated by a thumb or hand lever b², all of which may be of the usual or of any preferred form. This lever B may be pivoted, as at b³, to the standard A, and is preferably provided with oppositely-extending arms b⁴ at right angles thereto, so as to form a substantially T-shaped lever whose arms extend

on opposite sides of said standard. The arms of the lever B are preferably of equal length and provided near their outer ends with pendant brackets c c', which may have their upper ends forked, so as to be slipped over the ends of said arms and preferably rigidly secured thereto by bolts c¹ c² or otherwise, and with forked lower ends in which are arranged the loose pulleys c³ c⁴. These pulleys may be journaled upon studs or shafts c⁵ c⁵, which pass through apertures in the brackets c c', or the pulleys may rotate in unison with said shafts. Each pulley is preferably provided with independent grooves in which the ends of the chains or connections d d', leading to the signal or other movable body, and the ends of the chains or wires e e' are secured, the latter being provided at their lower ends with suitable weights e² e³, adapted to keep a constant tension upon the connections in whatever position the operating-lever B may be placed. The pulleys c³ and c⁴ and the weights e² e³, arranged on said pulleys, are preferably at substantially the same distance from the fulcrum or pivot of the lever B and are arranged so as to practically balance each other, thereby adding little, if any, to the force required to operate said lever, at the same time keeping a proper tension upon the connections d d', the position of the fulcrum varying according to the position of the journals of the pulleys and the manner of supporting said pulleys upon the lever.

The connections d d' may pass under pulleys f f', located, respectively, on opposite sides of the standard A or in any convenient position, and may connect in the usual manner to a semaphore or signal, as at G, or to any other movable body. This signal may be of the usual or of any desired form provided with the semaphore or signal arm g, the pivoted lever g', connected to said arm, and the wires g² g³, leading to the connections d d', respectively, the signal-arm being shown in the "danger" position, which occurs when the lever B is thrown to the right from the position illustrated.

For the purpose of notifying the operator that the signal has not responded to the movement of the lever B, I prefer to provide arms or indicators h h' for the connections d d', respectively, as shown diagrammatically in Fig. 1, the normal position of said arms being horizontal and arranged convenient to the operator, so that he may readily see the same. These arms or indicators h h' have their ends connected to the brackets c c' or other movable portion of the lever B by wires or other suitable connections h² h³, passing around the pulleys h⁴ h⁵, secured, respectively, to the connections d d', said connections h² and h³ having sufficient slack therein to permit the usual movement of the operating-lever. If the lever B is moved to the right, for instance, the connection d and pulley h⁴ will move therewith without operating said arms or in-

dicators; but should the connection d slip on the pulley c⁴ or become disconnected above the pulley h⁴ during the movement of the lever, the said pulley will not travel with the lever or will move in an opposite direction thereto and will cause said lever to pull upon the wire h², so as to increase the distance between said pulley h⁴ and the securing-point of the wire h² to the operating-lever, so that the arm h will be raised to the position shown, thereby indicating that something is wrong with the connection between the operating-lever and the signal. By moving the lever B toward the left the same result will be obtained except that the arm or indicator h' will be raised by the wire h³ in case the connection d' should slip or become disconnected from the pulley c⁴ or should break above the pulley h⁵.

To prevent the rotation of the pulleys when the lever B is operated and to assist the weights to insure a response from the signal, I may provide brakes k k, slidingly held upon the brackets c c' or any other suitable portion of said lever and adapted, when given a vertical movement, to engage the periphery of the pulleys c³ c⁴. These brakes may be of any preferred form and operated in any desired manner and may consist of shoes k k, provided with guide-arms k² k², having slots 95 through which a polygonal or other portion of the spindles or shafts c⁵ c⁵ of the pulleys c³ c⁴ pass, so as to guide the brakes and prevent the same from rotating with said pulleys. The upper ends of the guide-arms are 100 preferably connected to wires, chains, or other connections k³ k³, which have their inner ends connected to a wire or chain k⁴, and which pass around antifriction-rollers carried by the lever B, the wire or chain k⁴ being connected to the pawl b', so as to be operated by the hand-lever b² when the pawl is raised to operate the lever, so that simultaneously with the release of said pawl the wires or connections between the brakes will cause the latter 110 to engage the pulleys to prevent the rotation of the same. By this means there is no possibility of the pulleys rotating on the shafts c⁵ c⁵ should the connections d d' become caught or should the signal from any cause not readily respond to the movement of the main operating-lever.

The operation of the invention will be readily understood from the foregoing description when taken in connection with the accompanying drawings. It will be readily seen, should the lever B be moved to the right, that the connection d will throw the semaphore blade or arm g to the position shown. At the same time the weight e² will take up any slack 125 in the wires, while a movement of said lever in the opposite direction will place the signal in a position indicating "safety," any accident to the connection between the signal and the lever being readily ascertained by the position of the arms h h', as heretofore explained. I thus provide a simple, inexpensive, and con-

venient means for compensating for contraction and expansion in the signal-operating wires, at the same time providing a positive connection between the signal and the operating-lever, so that the signal will readily respond to the movements of said lever.

Instead of providing chains or wires carrying weights at their ends, as shown in Fig. 1, I may in some instances provide pulleys which have one side thereof weighted by casting the same solid, as shown at c^6 , Fig. 3, or by filling one side of the pulley with lead or other material of sufficient weight to take up the slack and provide proper tension for the signal-operating connections; or weighted pulleys, as in Fig. 4, may be provided, which are adapted to be held eccentrically in the brackets $c' c'$ of the operating-lever, the weighted portions of said pulleys being so disposed with relation to the connections $d d'$ that the slack in said connection will be taken up and a tension constantly exerted upon the same.

The pulleys $c^3 c^4$ may have a serrated surface or periphery adapted to be engaged by like serrations on the shoes in order to assist in preventing the rotation of the pulleys when the brakes are applied thereto, or a clutch or any other suitable means may be provided to rigidly hold said pulleys when the lever B is operated.

It is of course understood, where the word "connection" is employed, that chains, wires, or a combination of the same may be used, and that either one or its equivalent may be interchangeably used for the other when convenient. The general form or style of the pulleys may be changed, and instead of the arms $h h'$ any suitable indicator, signal, or pointer may be used to inform the operator in case the distant signal did not respond to the movement of the operating-lever.

Having thus fully described my invention, what I claim as new, and desire to secure by Letters Patent of the United States, is—

1. In a compensator, the combination with a suitable support, of an operating-lever pivoted thereto, independently-weighted pulleys arranged upon said lever at substantially the same distance from the pivot so as to practically balance each other at all times, together with connections secured to said pulleys and adapted to operate a movable body and have the slack therein taken up by said pulleys, whereby the lever may be readily operated and the slack taken up in the connections, substantially as described.

2. In a compensator, the combination with a suitable support, of an operating-lever provided with oppositely-extending arms pivoted to said support, pulleys arranged upon the arms of the lever at substantially the same distance from the pivot so as to practically balance each other at all times, connections adapted to operate a suitable body, and separate weights for the pulleys adapted to constantly exert a tension upon said connections

so as to take up the slack therein, whereby the lever may be readily operated and the slack taken up in the wires, substantially as described.

3. The combination with a suitable support, of an operating-lever pivoted to said support and provided with oppositely-extending arms, pulleys arranged upon said arms, connections having their ends secured to the pulleys and adapted to operate a signal, and separate weights secured to chains depending from said pulleys so as to practically balance each other and adapted to exert a tension upon said connections to take up the slack therein, whereby the lever may be readily operated and the slack taken up in the wires, substantially as described.

4. In a compensator, the combination with a suitable support, of an operating-lever pivoted to said support and provided with oppositely-extending arms, pendent brackets arranged upon said arms, pulleys journaled in said brackets, connections having their ends secured to the pulleys and adapted to operate a signal, chains having one of their ends secured to the pulleys, together with weights secured to the lower ends of said chains so as to practically balance each other and adapted to constantly exert a tension upon the connections so as to take up the slack therein, whereby the lever may be readily operated and the slack taken up in the wires, substantially as described.

5. The combination with a movable body, of an operating-lever, connections between said lever and the body, together with an indicator adapted to be operated by the lever should said body fail to respond to its movements, substantially as described.

6. The combination with a signal, of an operating-lever, connections between said lever and the signal, arms or indicators pivoted to a suitable support convenient to the operating-lever, pulleys carried by the connections, together with wires passing around the pulleys and having their ends secured to said arms and the operating-lever and adapted to be operated by said lever should the signal fail to respond to its movements, substantially as described.

7. In a compensator, the combination with a suitable support, of an operating-lever pivoted to said support, independently-weighted pulleys arranged upon said lever on opposite sides of its pivot so as to practically balance each other, connections secured to said pulleys and adapted to operate a movable body and have the slack therein taken up by said pulleys, together with means for engaging said pulleys to prevent the rotation of the same when the lever is operated to shift the signal, substantially as described.

8. In a compensator, the combination with a suitable support, of an operating-lever pivoted to said support, weighted pulleys arranged upon said lever so as to practically

balance each other, connections secured to said pulleys and adapted to operate a movable body and have the slack therein taken up by said pulleys, together with brakes 5 slidingly held upon said lever and adapted to directly engage the under surface of the pulleys; said brakes being connected to the lever so as to be simultaneously operated therewith to prevent the rotation of said pulleys

when the lever is shifted on its pivot, substantially as described.

In testimony whereof I affix my signature in presence of two witnesses.

JOHN ALBERT MARKLEY.
